(57) **CLAIM**

The ornamental design for a farming unit, as shown and described.

DESCRIPTION

FIG. 1 is a perspective view of a farming unit according to the present invention;

FIG. 2 is a front view of a farming unit according to the present invention;

FIG. 3 is a rear view of a farming unit according to the present invention;

FIG. 4 is a left side view of a farming unit according to the present invention;

FIG. 5 is a right side view of a farming unit according to the present invention;

FIG. 6 is a top view of a farming unit according to the present invention; and,

FIG. 7 is a bottom view of a farming unit according to the present invention.

The broken lines depict portions of the farming unit and form no part of the claimed design.

1 Claim, 7 Drawing Sheets
